UNITED STATES PATENT OFFICE.

ALLISON H. FLEMING, OF FAIRMONT, WEST VIRGINIA.

RAZOR-BLADE HOLDER.

1,147,226.

Specification of Letters Patent.

Patented July 20, 1915.

Application filed April 29, 1913. Serial No. 764,405.

To all whom it may concern:

Be it known that I, ALLISON H. FLEMING, a citizen of the United States, residing at Fairmont, in the county of Marion and 5 State of West Virginia, have invented a new and useful Razor-Blade Holder, of which the following is a specification.

My invention relates to a safety razor blade holder and more particularly to a device of this character adapted to be used 10 during the stropping of the blade.

The primary object of the invention is the provision of a device of this character adapted to be used with a blade having an elongated opening therein.

With the foregoing and other objects in view which will appear as the description proceeds, the invention resides in the combination and arrangement of parts and in the 20 details of construction hereinafter described and claimed, it being understood that changes in the precise embodiment of the invention herein disclosed can be made within the scope of what is claimed without departing from the spirit of the invention.

In the drawings: Figure 1 is a top plan view. Fig. 2 is a perspective view of the holder. Fig. 3 is a vertical sectional view on the line A—A of Fig. 2. Fig. 4 is a 30 longitudinal sectional view on the line B—B of Fig. 2. Fig. 5 is a detail view of the blade with which the holder is used.

In Fig. 1 of the drawings I have shown my blade holder in connection with a stropping device and this blade holder is formed from a sheet of metal and is bent into the form shown in Fig. 2 so as to form the two spring arm members 1 and 2 and the opening 3 through which a rod passes for securing the holder to the stropping device. The strip 4 is secured between the members 1 and 2 by means of the rivets 5.

An elongated depression 6 is formed in the member 2 so as to form a projection extending toward the other member, and as 45 shown in Fig. 4 of the drawing is adapted to substantially engage the member 1. This holder is adapted to be used with a safety razor blade of the construction shown in Fig. 5 of the drawing and this blade is provided with an elongated opening 7 through 50 which the depressed member 6 is adapted to pass when the blade is inserted between the spring members 1 and 2. The depressed member 6 is of such a size as to snugly fit

the opening 7 in the blade. By having a device of this construction it will be seen that the razor blade can be easily inserted into the holder by simply pushing it into the holder which will allow the members 1 and 2 to spring apart until the depressed member enters the opening 7 in the blade.

Briefly considered, the holder herein disclosed is fashioned from a strip of material bent upon itself to form a shaft receiving socket 3 and to form opposed resilient wings 1 and 2 projecting from the socket, the wing 2 being provided on its inner face with a blade holding projection 6 extended toward the wing 1. One or more securing elements 5 unite the wings. The strip 4 is located between the wings 1 and 2 and forms a closure for the edge of the socket 3, the securing elements 5 passing through the strip. The strip 4 serves to space the projection 6 from the inner face of the wing 1, against the action of the securing elements 5, thereby to define a blade receiving throat 50, between the inner face of the projection 6 and the inner face of the wing 1, as 70 clearly shown in Fig. 2. The strip 4 is not the mechanical equivalent of a structure which embodies an inward dishing of the wings 1 and 2 adjacent the socket 3, for the reason that the strip 4 may be of any desired 75 thickness, to space the wings 1 and 2 sufficiently to define the throat 50, whereas if the wings 1 and 2 were dished inwardly into contact adjacent the socket 3, no adjustment would be possible in order to define the 80 throat 50 without rebending the wings. Further, it is extremely difficult to bend the wings in the manner above specified, so that the bent portions of the wings will 85 contact with each other and still space the projection 6 from the inner face of the wing 1 to define the throat 50.

Having fully described my invention what I claim as new and desire to secure by Letters Patent is:—

A razor blade holder fashioned from a strip of material bent upon itself to form a shaft-receiving socket and to form opposed resilient wings projecting from the socket, one wing being provided upon its inner face 105 with a blade-holding projection extended toward the other wing; a securing element uniting the wings; and a strip through which the securing element passes, the strip being located between the wings and consti- 110

tuting a closure for the edge of the socket, the strip serving to space the projection from the inner face of said other wing against the action of the securing element, thereby to define a blade-receiving throat between the inner face of the projection and the inner face of said other wing.

Copies of this patent may be obtained for five cents each, by addressing the "Commissioner of Patents, Washington, D. C."

In testimony that I claim the foregoing as my own, I have hereto affixed my signature in the presence of two witnesses.

ALLISON H. FLEMING.
